UNITED STATES PATENT OFFICE.

WILLIAM JANNELL, OF WEST PARK, OHIO, ASSIGNOR TO THE DOMESTIC ELECTRIC COMPANY, OF CLEVELAND, OHIO, A CORPORATION OF OHIO.

FIBER-CRIMPING MACHINE.

Application filed March 28, 1921. Serial No. 456,146.

To all whom it may concern:

Be it known that I, WILLIAM JANNELL, a citizen of the United States, residing at West Park, in the county of Cuyahoga and 5 State of Ohio, have invented a certain new and useful Improvement in Fiber-Crimping Machines, of which the following is a full, clear, and exact description, reference being had to the accompanying drawings.

10 My invention relates more particularly to a machine designed to form up pieces of material from a continuous strip for the purpose of using them as an insulating material in the openings or slots of a field or armature, into which the wires are wound. This invention is more particularly concerned with small electric motors designed for domestic purposes. The armatures of these motors must be made very cheaply. They 15 are generally laminated and the result is that in large production some slight burr is likely to be left on the edges and the separate laminations are likely to be somewhat disaligned, so that if the insulated wire were 20 wound directly upon the armature, the result would be that the delicate insulation would be broken, since a small and delicate wire must be employed. It is therefore important that a cheap and effective insulating 25 and protecting means be inserted to form a protection for the wires. And it is a special object of this invention, therefore, to provide for the rapid and cheap production of 30 such an insulating means. The material best adapted for such use is a fibrous material, which is of a stiff and springy nature.

Where the material to be operated upon is either of a delicate or of a stiff nature, it is found to be difficult in prior machines to 35 properly feed it to the forming mechanism. An object of my invention is to provide a machine in which the material, whatever its grade, shall be positively guided and held in position throughout its travel through the 40 machine.

Another object of my invention is to provide a machine attaining the above objects, which feeds the material intermittently so as to allow it to be properly formed and to be 45 cut into pieces of the desired length.

Another object of my invention is to provide a machine of this kind to which the amount of material fed and the length of the strip cut, may be easily varied without

interfering with the correct operation of the 55 mechanism.

Other objects of the invention will be apparent in the course of the following description, and the features of novelty will be pointed out in the claims.

In the drawings in which a machine embodying the principles of my invention is illustrated, Fig. 1 is a top plan view of the machine, some parts being broken away and shown in section; Fig. 2 is a side view of the machine; Fig. 3 is an end view taken from the right of Fig. 2; Fig. 4 is a section on the line 4—4 of Fig. 1; Fig. 5 is an end view taken from the left of Fig. 1; Fig. 6 is a fragmentary section on an enlarged scale 60 taken on a plane transverse to the axis of the forming rolls and Fig. 7 is a perspective view of the product produced by the machine.

The device in general, comprises a pair of forming rolls A, die members B, and a cutter C. The forming rolls are intermittently driven so as to feed the strip of material between the die members when they are open and the cutter C is actuated while the die members are closed and serves to cut off a 65 pre-determined length of material after it has been shaped up in the die. Adjusting means are provided for changing the amount of feed of the rolls and consequently the 70 length of the strip cut off at each operation 75 of the cutter.

Referring more particularly to the drawings and to the different parts by numerals; the frame 10 carries the bifurcated standards 11 which are adapted to receive a spool or core 15, carrying wound thereon the roll R of fibrous material and support the roll 80 rotatively thereon. This frame and the standards may be independent of the framework of the main machine or may be a part 85 thereof as desired. The frame carries stems 12 on which are mounted the holding blades 13. These stems 12 may extend through suitable bosses on the standards 11 and are 90 adapted to be adjusted therein towards and from each other and to be clamped in such 95 adjusted positions by suitable means such as the set-screws 14. The blades 13, when properly adjusted therefor, serve to hold roll R from sliding on its shaft and guide the 100 strip as it is wound off of the roll.

The machine proper comprises a frame 20 having suitable standards thereon for sup-

porting the various shafts and dies. They will now be described.

The forming rollers A comprise the lower roller 30 which has a grooved or troughed face into which the complementarily formed face of wheel 31 is adapted to fit. These wheels are carried respectively on the shafts 32 and 33 and may be caused to rotate with these shafts by being pinned thereon as illustrated. The shaft 32 is journaled in the standards 21 of the frame 20 while the shaft 33 is journaled above this shaft in blocks 34 which may be slidably mounted in the bifurcated upper end of this standard, the springs 35 bearing on the closure plates 35' and on the blocks respectively, serving to hold the rolls in tight but yieldable contact in a well-known manner.

In order to provide a positive drive between the shafts, I show the spur gear 36 which is pinned on the shaft 32, in mesh with the spur gear 36' pinned on the shaft 33. These gears are designed to provide approximately the same peripheral speed on each of the wheels 30, 31.

In order to provide for an intermittent feed for these wheels, I have shown a spring release ball clutch which comprises the inner member 37 pinned to the shaft 32 and the member 40 which is rotatably mounted about this shaft and about the member 37. One end of a link 41 is pivotally secured to the member 40 by a stud 40^a, the other end of this link being pivoted to the third class lever 42, having its fulcrum at 43.

The lever 42 has a slot 47 formed therein and adapted to receive a crank pin 46 and bushing. The drive shaft 44, which is journaled in suitable standards on the frame, has at one end a guideway 45, in which is the crank pin 46 slidably mounted for radial motion relative to the shaft. The screw 48 which is threaded in an upstanding flange on the guide 45, and serves to adjust the position of the crank pin, and a locking nut 48' may be provided to hold the pin in its adjusted position.

It will be seen that by changing the position of the crank pin 46 on the guide 45, the motion of the lever 42 corresponding to a revolution of the shaft 44, may be varied and the amount of the corresponding step by step rotation of the rolls 30 and 31 will be varied accordingly.

In order to properly guide the strip of material between the rolls 30 and 31, I provide a guide member 50 which may be attached by suitable means such as screws to members 49 extending transversely from the standards 21 of the frame 20.

The lower face of member 50 has a rib formed therein complementarily to a V-shaped channel in the member 51 (see Fig. 3, reference character 56). This rib is pro-

gressively widened towards the end closest to the paper roll R. At this end the V is completely flattened out as shown at 52 in Fig. 3. Adjacent the edges of the V rib, member 50 has the side flanges 55, and fitting into the recess thus formed is the member 51, having complementarily formed faces fitting adjacent the faces of member 50 and held in position by suitable means such as the screws 54. The complementary V faces of the members 50, 51, are slightly separated so as to leave a guide groove 56 therebetween and the strip S of fibrous material is therefore positively guided in this groove, and formed up into a trough as the strip approaches the rolls, so that the strip is positively guided and held in form throughout the length of the member 50. These faces flatten out to form a straight slot 52 and the end of the guide members 50, 51, farthest from the rolls 30, 31, as above stated. It should be noticed that the vertical wall of member 50 in which the member 51 fits, forms a positive guide for the edges of the strip of material as it is fed to the rolls and positively prevents its disalignment.

Adjacent the rolls 30 and 31, the members 50 and 51 extend between the ends of the cross pieces 49 and into close proximity with the rolls. The construction and operation of these members are clearly illustrated in Figs. 3 and 6. If desired the members 49 and 50 may be readily made of an integral casting.

As the material passes through the rolls 30 and 31, it is further formed up to correspond to the shape of the rolls so that the guide members 50 and 51 serve to give the strip a natural and accurate feed into the rolls.

As the strip is fed through the rolls, it passes out and is received by a die member 61 preferably of hardened steel, which is carried in a groove in the bed block 70, mounted on the supports 22 of the frame. This die member has one end extending out of this groove and into close proximity with the rolls as clearly shown in Figs. 2 and 6. Suitable set screws 53 threaded in the bed 70 may be employed to firmly hold the die in position in the groove. The die 61 has a V-shaped trough 72 formed with sides which are progressively steeper away from the rolls.

In order to properly hold the strip of material in this trough, suitable spring strips 62 are provided which may be mounted by means of a set screw 63 on the bed 70. These strips extend along the bottom of the groove, one of them projecting towards the rolls and the other away from the rolls. The end of the strip adjacent the rolls is bent upward to insure guiding of the strip underneath it. As the strip 130

progresses along the guide trough, its middle portion is held downward into the center of the groove.

Overlying a portion of this female die 61 is the male die 64 which is adapted to be moved into and out of the groove of the member 61. This die is carried on a block 65 which may conveniently be made to extend approximately throughout the length 10 of the bed 70, but the die 64 itself extends only along a portion of this block as seen in Fig. 2. So that strictly speaking only the left hand portion of member 61 constitutes a female die, while the rest of these members 25 performs merely the function of a guiding trough.

Adjacent the die 64, the spring member 62 is bent up so as to prevent catching of the strip on the spring as the strip slides out 20 from under the spring.

The block 65 on which the die is carried is pivoted on a lever 66. This connection may be preferably affected by means of the pin which passes through a boss on the end of 23 the lever and through the elongated registering slots 71 in the ears on the upper end of the block 65. This loose pivoted connection allows the male die 64 to properly fit into the groove of the female die 61 as the 33 male die is forced down by the lever.

In order to actuate the lever 66, a steel insert 68 is provided thereon, which rides upon a cam 69 mounted on the shaft 80 which is journaled in suitable bearings on 35 the frame. The lever may be suitably pivoted as shown at 67, between standards 23 of the frame. In order to hold the lever in contact with this cam, I have provided a tension spring 81 suitably attached at one 40 end to the lever and at its other end to the frame.

The form of the cam should be such as to allow the male die to be held down into the female die for as long time as is possible 45 without interfering with the feed of the strip so that the male die 64 will rise just before the feeding action begins, and will again be forced down after the feeding ceases.

Within the bed 70 suitable heating means 50 may be provided such as the electric coil 82 extending through the length of the bed, having one end covered by means of a suitable plate 75, while the other end may be 55 suitably closed by a plate on the coil member. This coil serves to heat the die and the strip therein to cause the strip to be formed and given a final set into the trough-shaped form shown in Fig. 7.

It will be seen from the form of the cam 60 64 that the male die 64 is held in raised position during a portion of the rotation of the cam and is then drawn down by the spring into the clamping position. The 65 cam 89 is adapted to operate in such rela-

tion with the feed of the roll mechanism A that the male die will be in upper position while the feed is taking place so as to allow the strip to be fed into position in the lower die. 70

After the strip is fed into position, the cam turns to the point to allow the die to move downward under the action of the spring 81 to firmly clamp the strip in the female die, and to thereby form the strip 75 and give it a permanent set, the die and strip being heated by suitable means such as the electric heating coil 82, which may be inserted in a suitable opening 73 in the block 70. This coil may be connected to a suitable 80 source of current by means of the lead wires 74.

Adjacent the end of the die a knife blade 83 is located, said blade being carried on a lever 84 pivoted on a support 85 extending 85 from and suitably attached to the bed 52. This lever constitutes a lever of the first class, having its fulcrum at 86. Mounted on this lever is a hardened steel insert 87 adapted to ride upon the cam 88 carried on shaft 80. A spring 89 attached at one end to the lever and at its other end to suitably attaching means on the frame, serves to hold the lever in contact with the cam 88. 90

This cam is formed so as to allow the 95 spring 89 to hold the knife in upper position during the greater part of the rotation of shaft 80. It has a portion extending outward somewhat abruptly therefrom to cause a quick downward stroke of the knife and 100 an immediate return. Adjacent the knife end of the lever a spring 90 is attached, a suitable stud 91 being provided on the lever to form a means of attachment for the end of the spring. The other end of this spring 105 is attached by means of the screw 93 to the bed 70. This spring insures that the knife shall be held in operative relation against the shearing edge of the die 51, as the knife makes its downward cutting stroke, or 110 against a suitable cutting block which may be carried by the die 51. The formation of a cam which has been described, causes a sudden blow to be struck so that the knife shears the fibre with a clean cut. The form 115 of the product P thus produced is shown in Fig. 7.

In order to take up the shock or vibration 120 which might occur upon the return of the knife to upper position by means of the spring 89, I have shown the end of the lever 84 turned downward as at 94 and mounted beneath this end of the lever is a buffer 95 which may be carried by means of a collar 96, having a threaded shank 97 screw threaded in a boss mounted on the frame of the machine. A locking nut 98 may be provided to lock the buffer in adjusted position. 125

In order to drive the machine suitable 130

means may be provided such as the pulley 99 mounted on the shaft 44. This shaft may have pinned thereon a miter bevel gear 100, meshing with a miter bevel gear 101 pinned on the shaft 80. This insures the same speed of rotation of the shafts which is necessary to secure proper co-ordination between the feed of the rolls 30, 31, and the action of the cams 69, 88. Each of these shafts may be journaled at any desired points along their lengths on suitable standards carried by the frame 20 of the machine.

The shaft 44 also carries the crank pin guide 45 in which the crank pin 46 is slidably mounted as has been previously described.

The operation of the machine is as follows:

20 The strip of material to be operated upon is placed in position in the standards 11 and the end is brought down under the plate 50 and may then be fed into the rolls A. Power may be supplied to the machine by means of the pulley 99 and this will cause a rotation of the shaft 44 and an oscillation of the lever 42, which by means of the link 41 will cause oscillation of the rotary member 40. The member 37 which is pinned on the shaft 32 can receive rotation from the member 40 in one direction only so that the shaft 32 is given an intermittent step by step rotation in a counterclockwise direction as seen in Fig. 2.

35 The meshed spur gears 35 and 36 serve to communicate motion from shaft 32 to the shaft 33, which therefore revolves in a clockwise direction as seen in Fig. 2, so that the forming rolls 30 and 31 which are pinned respectively on these shafts have a similar intermittent rotation, and will feed the strip intermittently through the rolls. When the strip extends outward to the left of the rolls A in Fig. 2, the spring members 40 62, will serve to hold the middle portion of the strip in position in the channel of the die 61.

50 As additional portions of the strip are fed through the rolls, the strip will soon extend outward to such an extent as to occupy the whole of the channel of the die 61.

The coil 82 within the bed serves to heat the die and the strip therein, and on account of the reciprocating motion of the die 64 the 55 end of the strip which lies underneath this die will be clamped between the dies and given a permanent set. The action of the cam 69 with relation to the feeding motion is such that the die is held in upward position while the strip is being fed forward and is held downward during the time when no feeding action is taking place.

60 The cam 88 which operates the knife 83 is so arranged as to cause the cutting stroke of this knife to take place while the die 64

is in down or clamping position so that a clean cut of the strip is secured because the portion adjacent the knife is held firmly in position by means of the two dies 61 and 64. A portion of the strip is therefore cut off, 70 which is of the form shown in Fig. 7.

As the strip progresses from the original roll R to the forming rolls A, the guide members 50 and 51 serve to positively guide it throughout its course so that the strip is 75 always correctly fed to the rolls.

As the strip passes out from the rolls, it is received by the guide members 61 and 62 which serve to positively and accurately guide the strip to the dies so that the strip is 80 positively held in proper position throughout its course through the machine.

These guides have the progressively formed faces so that there is no abrupt change in the form of the strip at any point; 85 instead it is gradually and naturally formed into its final shape. It is given its final set, however, by the action of the die members, which are preferably heated. The final product P produced is shown in Fig. 7. 90

It will be apparent that if it is desired to alter the length of the strip it is only necessary to change the position of the crank pin 46 in its slide 45 so as to vary the length of stroke of lever 42 and consequently to 95 vary the corresponding rotation of the rolls 30, 31.

During the feeding operation of the machine, the guide blades 13 which extend along the side of the roll R serve to hold the roll and the material thereon in proper alignment so as to feed the strip correctly to the guides 50, 51 and to the machine.

It will be apparent from the foregoing description that I have provided a device 105 in which the material to be formed is positively and correctly fed to the different operating mechanisms and in which the material is gradually and naturally formed up into the desired shape, as it progresses to 110 and through the various mechanisms.

It will also be seen that I have provided a machine in which the length of the product produced may be readily varied within wide limits without in any way interfering with the proper operation of the machine. 115

The arrangement of the knife and its coordination with the operation of the die insures a clean cut of the material.

It will also be seen that the machine is 120 simple in construction and operation and may be cheaply manufactured, while at the same time, it is capable of forming the product at a rapid rate.

While I have described a specific embodiment of my invention it will be apparent that many changes might be made therein and that many different forms of mechanism embodying the principles of my invention might be made, and the foregoing descrip- 125 130

tion is therefore to be taken as illustrative of a specific embodiment of the invention rather than as restrictive of the character and scope of the invention.

5 Having thus described my invention, I claim:

1. In a device of the class described, a stationary and a movable die member, a knife adapted to cooperate with the stationary member to cut a piece of material therein, means for actuating the knife when the die is closed and resilient means for holding said knife in cooperative relation with said die when the knife is actuated.

15 2. In a device of the class described, a bed block carrying a stationary die member, a movable die member in cooperation therewith, a lever carrying a knife adjacent said stationary die, means for actuating said knife when the die is closed and a spring connecting said lever and block adapted to hold the knife in cooperative relation with the die when the knife is actuated.

25 3. In a device of the class described, a die adapted to be opened and closed, a guide comprising a groove for guiding a continuous strip of material to said die, and a spring in said groove for holding the material in a preliminarily formed condition in place therein.

30 4. In a device of the class described, the combination of a die adapted to permanently form up a strip of material, stationary guides adapted to preliminarily form up such material and direct it to said dies, and means for feeding the material when the die is open.

35 5. In a device of the class described, male and female members, one mounted on a lever, a lever carrying a knife adjacent to the other die member and means for operating said lever to actuate the knife when the die is closed.

40 6. In a device of the class described, a lever, male and female die members, one being carried on a block, said block and lever being adjustably pivoted together to allow accurate mating of the die members by means of a slot and pin connection, a knife adjacent the other die and means for operating said lever and knife in such relation that the knife is actuated when the die is closed.

45 7. In a device of the class described, a die member mounted on a bed, a die mounted on a lever and overlying said first named die, a lever carrying a knife adjacent said stationary die, means including a cam shaft having cams thereon, for actuating said levers in timed relation whereby said knife is adapted to cut off a length of material after it has been formed up by said die, and while it is extending outward therefrom.

50 8. In a device of the class described, a pair of rolls having complementary forming

faces, means for rotating said rolls, a member having a slot therein adapted to positively guide a strip to said rolls, a second member closing said slot and acting on the edges of the strip, said slot gradually assuming a shape similar to the shape of said faces as it approaches the rolls.

55 9. In a device of the class described, a pair of rolls one having a male and the other a female forming face, means for rotating said rolls, a guide member having a face progressively formed up to conform to the face of one of said rolls, another member having a complementarily formed face and adapted to be carried by the first member with its face adjacent the face of said first named guide member, whereby a strip of material may be positively guided to the rolls in the slot formed by the two members.

60 10. In a device of the class described, a pair of feed rolls adapted to feed a previously formed continuous strip of material, resilient means for holding said rolls in contact, means for intermittently driving said rolls, a die adapted to receive material fed by the rolls, and means for opening said die as the rolls are actuated.

65 11. In a device of the class described, a forming roller having a concave face, a complementary roll having a face adapted to conform therewith, said rolls being adapted to receive a strip of previously formed material, means for intermittently rotating said rolls and means for adjusting the amount of rotation of the rolls.

70 12. In a device of the class described, the combination of a pair of rotatable forming rolls having complementary faces adapted to form up and feed a strip of previously formed material therebetween, stationary guiding means adjacent said rolls and adapted to gradually form up the strip as it approaches the rolls.

75 13. In a device of the class described, the combination of forming rolls having complementary faces adapted to form up and feed a strip of material therebetween, stationary guiding means adjacent said rolls and adapted to gradually form up the strip as it approaches the rolls and means for giving said strip a set trough shape.

80 14. In a device of the class described, superimposed rolls having complementary formed faces adapted to feed and form a strip of material, a guide adjacent the rolls and adapted to gradually form up the material to the form of the rolls, a receiving guide adjacent the rolls adapted to receive the material from said rolls, die members comprising male and female dies having complementary faces adapted to further form up said strip, said receiving member extending into proximity to said dies and acting to gradually form up the strip in the form of the die faces.

15. In a device of the class described, superimposed rolls having complementarily formed faces adapted to feed and form a strip of material, a receiving guide adjacent to the rolls adapted to receive the material from said rolls, die members comprising male and female members having complementary faces adapted to further form up said strip, said receiving member extending 10 into proximity to said dies and acting to gradually form up the strip in the form of the die faces.
16. In a device of the class described, superimposed rolls having complementarily formed faces adapted to feed and form a strip of material, a guide for positioning and positively guiding said strip to the rolls, a receiving guide adapted to receive material from the rolls, die members having 15 complementary faces adapted to further form up said strip, said receiving guide extending into proximity with the rolls and die and adapted to positively guide the strip to the dies.
17. In a device of the class described, superimposed rolls having complementary faces adapted to form a strip into trough shape and feed it therethrough, a receiving member adjacent said rolls, having a channel of similar form gradually becoming steeper to form up the strip and similarly formed die members for receiving the strip therefrom and giving it a permanent set.
18. In a device of the class described, superimposed rolls having complementary faces adapted to form a strip into trough shape and feed it therebetween, a receiving member adjacent said rolls, having a channel of similar form gradually becoming steeper to form up the strips and a similarly formed die member for receiving the strip therefrom and giving it a permanent set, and means for heating said die.
19. In a device of the class described, the combination of superimposed rolls, having complementary formed faces adapted to form up a strip into the trough, means for intermittently rotating said rolls, a receiving member adjacent the rolls and adapted 45 to guide the strip, said member having a groove therein with progressively inclined sides, springs in said groove adapted to hold a strip therein, and forming die members adapted to receive the strip from said trough, and means for opening said die members while the strip is being fed forward by the rolls and closing it when the strip is stationary.
20. In a device of the class described, the combination of superimposed rolls, having complementary formed faces adapted to form up a strip into a trough shape, means for intermittently rotating said rolls, a receiving member adjacent the rolls and 50 adapted to guide the strip, said member

having a groove therein with progressively inclined sides, springs in said groove adapted to hold a strip therein, and forming dies adapted to receive the strip from said groove, means for opening said die while the strip is being fed forward by the rolls and closing it when the strip is stationary, means for heating one of said dies and the receiving member and means for cutting said strip while the die is closed.

21. In a device of the class described, a die member mounted on a bed, a die mounted on a lever and overlying said first-named die, a lever carrying a knife adjacent said stationary die, means including a cam shaft 70 having cams thereon for actuating said levers in timed relation whereby said knife is adapted to cut off a length of material after it has been formed up by said die, and while it is extending outward therefrom and intermittently rotated forming rolls adapted to feed a strip of material to the die when it is open.

22. In a device of the character described, the combination of a pair of feed rolls having complementarily formed faces, one of said rolls having a male face, the other of said rolls having a female face adapted to coact in forming a strip of material, means for rotating the rolls, a member having a slot formed therein, said slot having a substantially horizontal surface at one end progressively converging to slanting surfaces approximating the shape of the face of one of the rolls, a second member superposed on the first member to enclose the slot, said second member having surfaces complementary to the first member and at one end approximating the shape of the face of said second roll whereby a preliminary forming of the material being fed and formed by said rolls, may be effected.

23. In a device of the class described, the combination of a pair of feed rolls adapted to form a strip of material into a V-shape 110 as it is fed thereby, a pair of V-shaped clamping members having complementary faces adapted to grip said formed strip, guide means disposed between said rolls and said members, and a knife member cooperating with the ends of said gripping members to shear the formed strip into predetermined lengths.

24. In a device of the character described, the combination of a pair of forming rolls, a clutch mechanism associated therewith and arranged to drive the rolls intermittently, a pair of forming dies arranged to act on a strip of material formed by said rolls, a cutter associated with said dies for cutting the formed strip into predetermined lengths, a mechanism carrying said cutter and a separate mechanism carrying one of said die members, whereby the die and the cutter may be alternately oper- 120 125 130

- ated, and actuating means operating said last named mechanisms and said clutch mechanism in timed relation whereby the rolls may feed said strip of material when 5 the cutter and said die members are inactive.
25. In a device of the character described, the combination of a supporting bed, a die block mounted thereon, means for heating the die block, a lever member mounted on 10 the bed, a die member mounted on the lever member and in operative relation with said die block, a second lever member adjacent the first lever member, a cutter member mounted on the second lever member, a shaft 15 and cam members on the shaft arranged to successively operate said levers, whereby the die member may be in closed position on the die block when said cutter member is being operated.
- 20 26. In a machine of the character described, the combination of a pair of die members for gripping a strip of formed material, a cutter member associated with the ends of the die members for cutting the 25 formed strip into predetermined lengths, a lever member supporting one of the die members, a second lever member supporting the cutter member, a power shaft, a second shaft driven thereby, cam members mounted 30 on the second shaft for successively operating said levers, whereby the die members may grip the formed strip when the strip is being cut by said cutter member, a pair of feed rolls for forming the strip prior to the 35 feeding thereof to said die members, a clutch member associated with the feed rolls, and a crank mechanism connecting said power shaft to the clutch mechanism whereby the clutch mechanism is intermittently operable
- to grip the feed rolls during constant rotation of said power shaft. 40
27. In a machine of the character described, the combination of a pair of die blocks arranged to grip a formed strip of material, a cutter member associated therewith for cutting the strip into predetermined lengths, a pair of forming rolls adapted to intermittently feed the formed strip to said die members, a draw die for effecting a preliminary formation of the 50 strip as it is moved by the rolls, a clutch mechanism associated with the rolls, a continuously rotating power shaft, and an adjustable crank mechanism connecting the power shaft to the clutch mechanism, whereby the feeding operation of said rolls may be varied. 55
28. In a machine of the character described, the combination of a pair of feed rolls adapted to form a strip of material, a draw die associated with said feed rolls for effecting a preliminary forming of the strip of material as it is drawn therethrough by 60 the feed rolls, a pair of die members, one being movable, a cutter member for cutting 65 the formed strip of material into predetermined lengths, a clutch mechanism associated with the feed rolls for causing intermittent operation thereof, and actuating means acting upon the clutch mechanism, 70 the cutter and said die members for intermittently effecting operation thereof in timed relation whereby said die member and feed rolls are inactive when said cutter member is actuated. 75

In testimony whereof, I hereunto affix my signature.

WM. JANNELL.
